C. A. MADDEN

GAME APPARATUS

Filed Jan. 22, 1926

INVENTOR.
Charles A. Madden
BY *Gottschalk*
ATTORNEY

UNITED STATES PATENT OFFICE.

CHARLES A. MADDEN, OF BROOKLYN, NEW YORK.

GAME APPARATUS.

Application filed January 22, 1926. Serial No. 82,985.

This invention relates to a new and amusing device in the nature of a game, said device being particularly adapted to test the skill of the player.

5 The object of the invention is to provide a game of novel construction and arrangement of parts, hereinafter more fully described, claimed, and illustrated in the accompanying drawings in which,

10 Fig. 1 shows a side elevational view of my improved game.

Fig. 2 shows a top plan view thereof.

Fig. 3 shows a sectional view taken on the line 3—3 of Fig. 2.

15 Fig. 4 shows a similar view taken on the line 4—4 of Fig. 2.

Fig. 5 shows a similar view taken on the line 5—5 of Fig. 2.

As here embodied, my improved game 20 comprises briefly, a table top 10, preferably circular shaped, rigidly attached, at its center, to the upper extremity of a vertical rod 11, which is a slidable fit in a vertical tube 12, as at 13, the said vertical tube having a 25 set screw 14 attached at its upper extremity as a means of holding the heretobefore mentioned table top 10 in any desired extended position. The vertical tube 12 is attached, at its lower extremity, to the center of a base 30 15, preferably circular shaped, and having lower depending members 16, of any suitable shape and design, to support the said base, on the floor, table or any convenient place.

The table top 10 is provided with a circular aperture having a ledge 17, or shoulder 25 to support the pocket 18, by its rim 19, the said pocket being of woven cord, hemp, or any suitable material.

In order to close the said aperture, when 40 the pocket 18 is removed, I have provided a disc 20, of suitable diameter, pivotally attached to the upper extremity of the rod 11, as at 21, and having a handle 22 extending beyond the periphery of the table top 10, 45 the said disc 20 being a slidable fit in a suitable shaped aperture 23 located in the table top 10.

A similar pocket 24, somewhat smaller, than the heretobefore described pocket 18 is 50 similarly supported in the table top 10.

A third pocket 25 is similarly supported in a slide 26, which is of suitable shape, so as to be slid in an elongated arcuate aperture 27 having radial sides with ledges 28 to 55 support the slide 26. The slide 26 is shaped

arcuately similar to the aperture, so that the arcuate edges of the slide will rest upon the arcuate ledges 28 of the aperture 27. The above mentioned construction being such as will permit the pocket 25 supported from 60 the slide 26 to be moved to any desired position in said elongated aperture 27.

My improved game is played as follows. The players will in turn bounce a rubber ball, designated by the numeral 29, upon the 65 floor or table, and endeavor to bounce the said ball into one of the heretobefore mentioned pockets.

It is obvious that by sliding the pocket 25 into different positions, and also by closing 70 the pocket 18, that considerable skill will be required to accomplish the desired requirements.

While I have above described the preferred form, construction, and arrangement 75 of the several elements employed, it will be understood that the device is, nevertheless, susceptible of considerable modification therein, and I therefore reserve the privilege of resorting to all such changes as may be 80 plainly embodied within the spirit and scope of the invention as claimed.

Having thus described my invention, what I claim as new and desire to secure by Letters Patent of the United States is as follows:—

1. A game comprising a table having a fixed pocket and an arcuate aperture, and a slide carrying a second pocket fitting into 90 said aperture and capable of assuming different positions within said aperture with respect to the fixed pocket.

2. A game comprising a table having a circular opening for supporting a pocket and an arcuate aperture, a slide carrying a 95 second pocket fitting into said aperture and capable of assuming different positions within said aperture with respect to the fixed pocket, and means for closing said circular opening upon removal of the pocket therefrom.

3. A game comprising a table having a circular opening for supporting a pocket and an arcuate aperture, a slide carrying a second pocket fitting into said aperture and 105 capable of assuming different positions within said aperture with respect to the fixed pocket, and means for closing said circular opening upon removal of the pocket therefrom, said means including a disc movable 110

in a slot in the table adjacent the circular opening.

4. A game comprising a table top rigidly attached to a vertical rod, which is a slide fit in a vertical tube attached to a base, and a means of holding the said table top in any desired extended position, said table top provided with a circular aperture having a ledge to support a pocket by its rim, and a means of closing the said aperture, when the said pocket is removed, comprising a disc pivotally attached to the upper extremity of the said rod, and having a handle extending beyond the periphery of the said table top, the said disc being a slide fit in an aperture located in the said table top, and a second pocket similarly supported in the said table top, and a third pocket similarly supported in the said table top in a slide, a slide fit in an elongated aperture having radial sides with a ledge to support the said slide having sides to engage the said ledge, as a means of sliding the said third pocket to any desired position in the said elongated aperture.

5. A game comprising a table top rigidly attached to a vertical rod, which is a slide fit in a vertical tube attached to a base, and a means of holding the said table top in any desired extended position, said table top,

provided with a circular aperture having a ledge to support a pocket by its rim, and a means of closing the said aperture, when the said pocket is removed, comprising a disc pivotally attached to the upper extremity of the said rod, and having a handle extending beyond the periphery of the said table top, the said disc being a slide fit in an aperture located in the said table top, and a second pocket similarly supported in the said table top, and a third pocket similarly supported in the said table top in a slide, a slide fit in an elongated aperture having radial sides with a ledge to support the said slide having sides to engage the said ledge, as a means of sliding the said third pocket to any desired position in the said elongated aperture.

In testimony whereof I have affixed my signature.

CHARLES A. MADDEN.
